Inventor:
A.R. Fergusson
by his Attorneys,
Weed & Gray

UNITED STATES PATENT OFFICE.

ALAN R. FERGUSSON, OF BUFFALO, NEW YORK.

TOY RAILWAY.

Application filed April 17, 1923. Serial No. 632,600.

To all whom it may concern:

Be it known that I, ALAN R. FERGUSSON, a citizen of the United States, residing at Buffalo, in the county of Erie and State of New York, have invented certain new and useful Improvements in Toy Railways, of which the following is a specification.

This invention relates to toy or miniature railways, an object of the invention being to provide an improved efficient and relatively cheap means for releasably connecting or joining the adjacent or juxtaposed ends of a pair of wire rail track sections.

A further object of this invention is to provide in a toy or miniature railway an improved means for forming a releasable dowel joint between the ends of a pair of wire or cylindrical rails.

A further object of this invention is to provide in a toy or miniature railway a wire or cylindrical rail having an improved tubular or dowel receiving end for releasable connection with the dowel end of another rail, such as a wire or cylindrical rail.

25 A further object of this invention is to provide a wire or cylindrical rail for a toy railway having an improved dowel receiving end constructed to resiliently grip the dowel end of an adjacent rail so as to form a firm efficient joint and yet adapted to readily permit the release of the rail ends.

30 A further object of this invention is to provide in a toy or miniature railway an improved dowel joint for a pair of wire or cylindrical rails, the dowel joint being formed by means of a hollow or tubular member permanently interlocked with one rail end and adapted to be releasably interlocked with the other rail end.

40 A further object of this invention is to provide in a toy or miniature railway a wire or cylindrical rail having an improved dowel receiving end, the same comprising a bent up or coiled tubular member embracing a reduced or dowel end of the rail and having the juxtaposed edges thereof unconnected to form an expansible and contractible body.

45 Other objects of this invention will appear in the following description and appended claims thereof, reference being had to the accompanying drawings forming a part of this specification wherein like reference characters indicate corresponding parts in the several views and wherein Fig. 1 is a plan view illustrating a form of my inven-

tion; Fig. 2 is a fragmentary view partly in section illustrating the dowel joint; Fig. 3 is a fragmentary perspective view illustrating the cooperating ends of a pair of rails 60 adapted to form the improved dowel joint; Fig. 4 is a fragmentary perspective view illustrating a pair of juxtaposed rail ends having a somewhat modified form of dowel joint; Fig. 5 is a detail view of a rail end 65 thereof; Fig. 6 is a top plan view illustrating a further modified form of my invention; Fig. 7 is a bottom plan view of a rail section illustrating this embodiment; Fig. 8 is a fragmentary view illustrating a pair of 70 rails joined together; and Fig. 9 is a detail perspective view of a dowel receiving member.

Before explaining in detail the present improvement and mode of operation thereof, it is desired to have it understood that the invention is not limited to the details of construction and arrangement of parts which are illustrated in the accompanying drawings, since the invention is capable of 75 other embodiments, and that the phraseology which is employed is for the purpose of description and not of limitation.

In the drawings the track sections which are adapted to be releasably joined together 80 in accordance with my invention are preferably constructed of wire or cylindrical rails mounted upon wire formed across ties thereby forming wire track sections. In Figs. 1 to 3 inclusive it will be seen that 85 one of the track sections comprises spaced wire or cylindrical rails 9 and 10 extending in parallel relation and mounted upon wire or cylindrical cross ties 11, the rails being preferably secured to the cross ties as by 90 spot welding. One of the wire rails 10 is provided at the end thereof with a reduced or dowel end 12, this dowel being formed in any suitable manner.

The companion wire rail 9 of this track 100 section is also provided at its end with a reduced or dowel end 13. A hollow or tubular member 14 which may be formed by bending up or coiling a piece of sheet metal with the edges thereof juxtaposed and preferably unconnected to form an endwise extending slot 15, is placed over or slipped on to the dowel end 13 of the rail 9. It will be understood that the hollow or tubular member 14 is of sufficient diameter to snugly 110 embrace the dowel end 13 and the metal of this member is of sufficient thickness to cor-

respond to the depth of the shoulder 13^a formed by the reduced end 13. At the shoulder 13^a the abutting end 16 of the member 14 may be welded to the rail 9 thereby securely holding the same in position. The dowel receiving member or open tube ferrule 14 projects a suitable distance beyond the end of the dowel 13, and since the curved side walls thereof are separated by means 10 of the slot 15, this member will form an expandable and contractible body having spring gripping walls.

The adjacent track section which is to be joined to the rails 9 and 10 is preferably 15 constructed in substantially the same manner as hereinbefore described and comprises a pair of spaced parallel wire or cylindrical rails 18 and 19 secured as by spot welding to wire cross ties 20. The rail 18 is provided 20 with a dowel end 21, and the rail 19 is provided with a tubular or dowel receiving end 22 preferably of substantially the same construction as the member 14. The tubular member 22 in like manner has a lengthwise 25 extending slot 23, thus forming a gripping portion adapted to receive the dowel end 12. In construction the interior diameter of the tube or ferrule 14 will preferably be a few thousandths of an inch less than the diameter 30 of the dowel 21, and in like manner the interior diameter of the tube or ferrule 22 will be a fraction less than the diameter of the dowel end 12. Thus when the two track sections are joined together by inserting the 35 dowels in the dowel receiving members, the dowels will expand somewhat the open tubes 14 and 22, and the resilient walls thereof will grip the dowels and firmly maintain the ends of the rails in joined position.

40 In the somewhat modified construction illustrated in Figs. 4 and 5 the wire rail is also provided with an open tube or ferrule member which may be interlocked with the rail. In this instance the wire or cylindrical rail 24 is provided with a reduced or dowel end 25 forming a shoulder 26, the dowel having an upstanding lug or projection 27 formed therefrom in any suitable manner. The ferrule or tubular member 28 at one 45 edge thereof is provided with a square notch 30 and is bent up or coiled to embrace the dowel 25, the ferrule or tube being locked on this dowel by means of the lug 27 extending into the notch or recess 30. As in the 50 previously described construction the ferrule 28 is preferably formed of butted tubing with an open lengthwise extending seam or slot 29. The wire rail 33 which is to be joined to the rail 24 is provided with a 55 dowel end 32 which is tapered toward its end, and when this dowel is inserted into the tubular end 31 it will spring open or expand the same thereby forming an efficient friction or gripping joint. When the 60 dowel 32 is removed the spring walls of the

tubular member 28 will contract again to their normal position.

In the construction illustrated in Figs. 6 to 9 inclusive the juxtaposed track sections which are to be releasably joined together in like manner each comprises spaced parallel wire or cylindrical rails 45 and 45^a mounted upon and secured as by spot welding to wire or cylindrical cross ties 47. Each of the wire rails 45 and 45^a of a section is provided at one end with a dowel receiving member and at the other end with a dowel, both rails preferably constructed in substantially the same manner. As shown particularly in Fig. 8 the wire rails 45 and 45^a to be joined together are provided with juxtaposed dowel or reduced end portions 46 and 51 respectively, and lugs or projections 47^a and 52 are pinched out or otherwise formed from the dowels 46 and 51 in any suitable manner. A ferrule or tubular member 48 is bent up or coiled so as to embrace the dowel end 46 and is provided with a notch or recess 55 adapted to receive the lug 47^a. By means of the lug and notch the ferrule or tube 48 is locked in position on the dowel end 46 since the lug 47^a will impinge against the square corner 50 which prevents the ferrule from pulling off the end of the rail 45^a. It will be noted that the tubular member 48 is an open tube having the lengthwise extending juxtaposed edges thereof unconnected and forming an endwise extending slot 49 provided with a pair of spaced recesses or notches 54 and 55 for receiving lugs 52 and 47^a. The ferrule 48 extends beyond the end of the dowel 46 and is adapted to receive the dowel end 51 of the rail 45. At its entrance the slot 49 is tapered or flared outwardly at 53^a so as to permit the lug 52 to enter the slot 49 upon inserting the dowel 51 into the ferrule. Since the lug 52 is thicker than the width of the slot 49 it will spread apart or expand the end walls of the ferrule, which will again contract or close into normal position when the lug 52 becomes seated in a notch or recess 54 in the ferrule. With the rails joined together as shown in Fig. 8 and the lug 52 seated in the notch 54 it will be seen that the spring walls of the ferrule will normally tend to resist the removal of the dowel from the ferrule, but upon pulling the rails apart the lug 52 will engage the tapered or sloping wall 53 and spread the walls apart sufficiently to permit the lug 52 to pass through the slot 49 thereby releasing the dowel end 51. From this construction it will be seen that each of the rails 45 and 45^a of a section are first formed with interchangeable dowel ends having lugs or projections. Since all of the dowel ends are identical in construction thereby facilitating and economizing the manufacture of the sections, the ferrule or tube 48 may be 120

placed over and interlocked with either dowel end of each rail, the rails being positioned and secured to the wire ties so that the dowel ends and the dowel receiving portions of the two rails will be located at opposed ends of the sections as clearly shown in Figs. 6 and 7.

It is to be understood that by describing in detail herein any particular form, structure, or arrangement, it is not intended to limit the invention beyond the terms of the several claims or the requirements of the prior art.

Having thus explained the nature of my said invention and described a way of constructing and using the same, although without attempting to set forth all of the forms in which it may be made, or all the modes of its use, I claim:

1. In a toy railway a wire rail having a resilient tubular end.

2. In a toy railway a wire rail terminating in a resilient gripping portion.

3. In a toy railway a wire rail terminating in a tubular gripping portion.

4. In a toy railway a wire rail terminating in a slotted tubular end.

5. In a toy railway a wire rail terminating in a tubular dowel receiving end.

6. In a toy railway a cylindrical rail terminating in a dowel receiving end having resilient walls.

7. In a toy railway a solid metal rail terminating in a dowel receiving end having gripping portions.

8. In a toy railway, a metal rail having a dowel receiving end terminating in a pair of oppositely located expandible and contractible gripping portions.

9. In a toy railway a cylindrical rail terminating in a tubular member of the same diameter secured thereto, and adapted to be releasably joined to an adjacent rail end.

10. In a toy railway a cylindrical rail having a tubular member secured to the end thereof, said member having a lengthwise extending slot.

11. In a toy railway a wire rail having a dowel receiving portion comprising a piece of metal bent-up or coiled with the edges thereof juxtaposed.

12. In a toy railway a wire rail having a dowel receiving end portion comprising a piece of metal bent-up or coiled with the edges thereof juxtaposed edges thereof unconnected.

13. In a toy railway a cylindrical rail having a dowel receiving end portion comprising a piece of metal bent up or coiled to form a resilient gripping portion.

14. In a toy railway, a solid metal rail having a hollow dowel receiving member connected to the end thereof.

15. In a toy railway, a metal rail terminating in a tubular dowel receiving member of the same diameter secured at the end

thereof and adapted to be releasably joined to an adjacent rail.

16. In a toy railway a wire rail having a reduced end portion, and a dowel receiving portion connected to said end portion. 70

17. In a toy railway a wire rail having a reduced end portion, and a dowel receiving member comprising a piece of metal bent to embrace said reduced end portion.

18. In a toy railway a wire rail having a 75 reduced end and a tubular member having an interlocking connection with said end.

19. In a toy railway a wire rail having a reduced end and a tubular member having an interlocking connection with said end, 80 said connection comprising a lug and a recess.

20. In a toy railway a wire rail having a reduced end portion provided with a projecting lug, and a dowel receiving member 85 carried by said reduced end and having a recess for receiving said lug.

21. In a toy railway the combination of a pair of wire rails, one thereof having a resilient tubular end, and the other having 90 a dowel adapted to releasably extend thereinto.

22. In a toy railway the combination of a pair of wire rails, one thereof having a gripping portion for receiving the end of the 95 other wire rail.

23. In a toy railway the combination of a pair of metal rails having reduced ends, a dowel receiving member permanently connected to one of said ends and adapted to be 100 detachably connected to the other end.

24. In a toy railway the combination of a pair of wire rails terminating each in a dowel, a tubular member embracing one of said dowels and adapted to releasably receive the other dowel. 105

25. In a toy railway the combination of a pair of wire rails, one of said rails having a tubular end and the other having a dowel adapted to extend thereinto, said dowel having a diameter greater than the interior diameter of said tubular end. 110

26. In a toy railway the combination of a pair of wire rails adapted to be located end to end, a tubular member permanently interlocked with one rail end and adapted to be releasably interlocked with the other rail end. 115

27. In a toy railway the combination of a pair of wire rails adapted to be located end to end, a tubular member permanently interlocked with one rail end and adapted to be releasably interlocked with the other rail end, said tubular member and rail end having cooperating lugs and recesses. 120

28. In a toy railway a pair of wire rails having each a dowel end provided with a projecting lug, and a tubular member embracing a dowel end and having a locking recess for the lug thereof, said tubular mem- 130

ber extending beyond said dowel and having a slot with a recess for releasably receiving the lug of the other rail.

29. A toy railway section comprising a pair of spaced wire rails, each of said rails having a dowel at one end, and a dowel receiving portion at the opposite end.

30. A toy railway section comprising a pair of spaced wire rails, said rails at each end of the section having one a dowel end and the other a dowel receiving end, and one thereof projecting beyond the other.

31. In a toy railway the combination of wire ties, and wire rails connected thereto, one thereof having a tubular dowel receiving end.

32. In a toy railway the combination of

wire ties, and wire rails connected thereto, one thereof having a resilient tubular dowel receiving end.

33. In a toy railway the combination of a pair of wire rails, one thereof having a dowel end, and the other a dowel receiving portion for releasably receiving said dowel end.

34. In a toy railway the combination of a pair of sections including each wire ties and wire rails connected thereto, and means at the juxtaposed ends of said rails for forming a releasable dowel joint.

Signed at Buffalo, N. Y., this 12th day of April, 1923.

ALAN R. FERGUSSON.
